SNOW PLOW

Louis J. Litchy, Royalton, Minn.

Application July 15, 1937, Serial No. 153,839

2 Claims. (Cl. 37—44)

This invention relates to plows and more particularly to a plow especially adapted for removing snow from highways.

An object of the present invention is to provide a plow of such a structure that the weight of the snow being removed thereby will be sustained by the plow and not by the vehicle to which the plow is attached, an objectionable feature of the type of snow plows now generally used for this type of work.

A further object of the invention is to provide a snow plow having adjustable flareboards mounted on the mold boards of the plow.

A still further object of the invention is to provide improved supporting means for the plow including means for raising and supporting the point of the plow above ground level.

The invention together with its objects and advantages will be best understood from a study of the following description taken in connection with the accompanying drawings wherein:

Figure 1 is a side elevational view of the plow.

Figure 2 is a rear elevational view of the plow.

Figure 3 is a top plan view of the plow.

Figure 4 is a fragmentary detail sectional view of a rear portion of one of the moldboards of the plow, and showing the flareboards associated therewith.

Figure 5 is a fragmentary vertical sectional view through the plow showing a supporting assembly therefor.

Figure 6 is a perspective view of a ground engaging member and yoke associated therewith.

Figure 7 is a perspective view of a link assembly, and

Figure 8 is a fragmentary detail view showing the pivot rod and means for mounting the same.

Referring to the drawings by reference numerals it will be seen that in the preferred embodiment thereof the improved plow which is substantially V-shaped in top plan comprises a pair of moldboards 5—5 that diverge towards the rear of the plow and converge at the front of the plow where they are joined together with one another and with a forwardly extending centerboard 6.

The moldboards 5 are suitably equipped with blades 7 between the converging ends of which is disposed the plow point 8.

Each moldboard 5 at the upper edge thereof is also provided with a pair of flareboards 9, 10, flareboard 9 being hinged to the upper edge of its associated moldboard as at 11 and flareboard 10 being hinged to its companion flareboard as at 12.

For supporting the flareboards 9 and 10 at the

desired angular position of adjustment relative to one another and relative to the associated moldboard 5 there are provided for each pair of flareboards 9 and 10 adjustment devices 13 and 14 respectively.

The adjustment device 13 comprises a lug 14 mounted on the rear face of the moldboard 5 adjacent the upper edge of the moldboard while lugs 15 and 16 respectively are provided on the rear sides of the flareboards 9 and 10 as shown in Figure 4.

Pivoted to the lug 15 associated with the flareboard 9 as at 17 are links 18 and 19.

Link 18 is provided adjacent one end thereof with a series of openings 20 adapted to be selectively aligned with an opening in the lug 14 to receive a bolt 21 through the medium of which the flareboard 9 is secured at the desired position of adjustment relative to the moldboard 5.

Link 19 at its free end is provided with a series of openings 22 adapted to be selectively aligned with an opening in the lug 16 to receive a bolt 23 through the medium of which flareboard 10 is held at the desired position adjustment relative to its companion flareboard 9.

The adjustment device 14 comprises a lever 24 pivoted at one end to a bracket 25 mounted on a web plate 26 secured at the angle between the moldboards 5 rearwardly thereof. As best shown in Figure 2 the free end of the lever 24 is provided with a series of openings 27 adapted to be selectively aligned with an opening in a lug 28 on the flareboard 10 to receive a bolt 29 through the medium of which the lever 24 is adjustably secured to the lug 28 to cooperate with the adjustment device 13 for securing the flareboards at the desired angular positions of adjustment.

The plow is further provided with a hitch structure indicated generally by the reference numeral 30. Hitch structure 30 comprises a transverse bar 31 that extends between the moldboards 5 and at its respective opposite end is welded or otherwise made fast to the moldboards. Extending upwardly from intermediate portions of the bar 31 are short standards 32 which at their upper ends support a cross bar 33. Cross bar 33 is braced relative to the moldboards 5 through the medium of crossed diagonal braces 34.

Cross bars 31 and 33 are provided, as clearly shown in Figure 2, with laterally spaced pairs of spaced apertured ears 35, 36 that accommodate coupling pins 37, 38, through the medium of which the plow may be pivotally mounted on a suitable supporting structure that may extend forwardly

from a tractor, motor truck, or other analogous vehicle.

Also for steadyng the plow the moldboards 5 thereof at their inner sides and adjacent the rear of the plow are provided with angular brackets 39 in the horizontal portions of which are journaled bolts 40 having on their lower ends ground-engaging tread members 41. In the present instance, the tread members 41 are shown as consisting of blocks of wood or other suitable material having a tread surface of metal or other suitable material. However, it is to be understood that the tread members 41 may, if desired, be in the form of rollers.

Further in accordance with the present invention there is provided means for raising the point 8 of the plow out of engagement with the ground and for supporting the plow in this raised position. Such means, in the present instance, consists of a suitable screw jack 42 bolted, or otherwise secured as at 43 to a brace beam 44 that extends from the forward end of the plow to the upper cross bar 33.

The head 45 of the jack is such as to accommodate a rod 46 that is welded or otherwise positively secured to the head 45.

A pair of links 47 are provided at one end with apertures to receive the pivot rod 46 and these links are retained in engagement with the rod 46 through the medium of cotter pins 48 or as otherwise found desirable.

At their free ends the links 47 are pivoted through the medium of a pivot pin 49 to one end of yoke bars 50.

Yoke bars 50 intermediate their ends are pivotally supported between a pair of rearwardly extending angle bars 51 through the medium of a pin 52.

Pivoted between the free ends of the yoke bars 50 is a ground-engaging element 53.

In the present instance the ground-engaging element 53 is shown in the form of a block of wood, metal, or other suitable material but it is also to be understood that this ground-engaging element, if desired, may be in the form of a roller.

It will thus be seen that to raise the point end of the plow out of contact with the ground, the screw shank of the jack 42 is threaded upwardly. This will result in a swinging of the yoke arms 50 in a counter-clockwise direction to engage the ground-engaging member 53 with the ground with the result that as the shank of the screw jack continues upwardly the plow will be tilted rearwardly to raise the point 8 thereof above the surface of the ground. This will be found particularly desirable when the plow is moving over rough and bumpy ground.

Obviously, to lower the point into engagement with the ground the shank of the jack is lowered in the usual manner.

Also, in accordance with the present inven-

tion, the moldboards 5 of the plow are suitably reinforced by angle irons 54; and when it is desired to tow the plow a draft chain or the like may be readily engaged in an aperture 55 provided therefor at the lower end of the dividing board 6 of the plow.

It is thought that a clear understanding of the construction, utility and advantages of a plow embodying the features of the present invention will be had without a more detailed description, it being understood, however, that the invention is applicable to any type of plow, whether it be of the V-type shown, or of the wing type or one-way type; and that also the invention may be embodied in a plow of any size, large or small, as for example to render the plow useful for clearing railroad right-of-ways.

Having thus described the invention what is claimed as new is:

1. In a snow plow structure of the V type, a pair of rearwardly divergent moldboards, and means to connect said boards together comprising a lower rear cross bar extending laterally between said boards and having the ends thereof fixed to said boards, respectively, a frame of substantially rectangular form upstanding from said cross bar centrally thereof and parallel therewith, an upper connecting bar between the top of said frame and said boards extending horizontally in the longitudinal center of the structure, a pair of lower connecting bars between said cross bar and said boards, respectively, extending horizontally and parallel upon opposite sides of said center of the structure, respectively, and a pair of diagonal cross braces extending from opposite upper corners of said frame to said boards, respectively, and fixed to the latter adjacent the upper edges thereof.

2. In a snow plow structure of the V type, a pair of rearwardly divergent moldboards, and means to connect said boards together comprising a lower rear cross bar extending laterally between said boards and having the ends thereof fixed to said boards, respectively, a frame of substantially rectangular form upstanding from said cross bar centrally thereof and parallel therewith, an upper connecting bar between the top of said frame and said boards extending horizontally in the longitudinal center of the structure, a pair of lower connecting bars between said cross bar and said boards, respectively, extending horizontally and parallel upon opposite sides of the center of the structure, respectively, a pair of diagonal cross braces extending from opposite upper corners of said frame to said boards, respectively, and fixed to the latter adjacent the upper edges thereof, a front supporting shoe mounted on said pair of lower connecting bars to rock therebetween and a pair of rear side shoes fixed to opposite ends of said cross bar, respectively.

LOUIS J. LITCHY.
